CLOTH BOLT MACHINE

Henry C. Davis, Calhoun City, Miss.

Application January 4, 1939, Serial No. 249,338

3 Claims. (Cl. 33—127)

This invention relates to a cloth bolt machine, and has for the primary object the provision of a device of this character which will permit easy and quick removal of a desired length of cloth from a bolt of cloth and further permit the desired length of cloth to be accurately cut from the remaining cloth of the bolt of cloth and to remove the selected length of cloth in a folded condition ready for wrapping.

With these and other objects in view, the invention consists in certain novel features of construction, combination and arrangement of parts to be hereinafter more fully described and claimed.

For a complete understanding of my invention, reference is to be had to the following description and accompanying drawings, in which

Figure 1 is a side elevation illustrating a cloth bolt machine constructed in accordance with the present invention.

Figure 2 is a top plan view illustrating the machine.

Figure 3 is an end elevation illustrating the machine.

Figure 4 is a sectional view taken on the line 4—4 of Figure 2.

Figure 5 is a sectional view taken on the line 5—5 of Figure 2.

Figure 6 is a fragmentary transverse sectional view illustrating the means of supporting the cloth while cutting.

Referring in detail to the drawings, the numeral 5 indicates the base of a machine on which is mounted a supporting structure 6 especially constructed for the supporting of a bolt of cloth as illustrated at 7 and consists of relatively spaced elongated plates 8 which have their upper edges formed to slope in opposite directions providing inclined faces A and stop faces B coacting with each other in supporting a bolt of cloth as clearly shown in Figures 1 and 4 so that the bolt of cloth will be free to rotate thereon when removing cloth therefrom.

Mounted on the base 5 are vertically arranged standards 9 providing a journal for a horizontally arranged shaft 10 on which is mounted for free rotation a main cylinder 11 of a length substantially equal to the width of the base and is provided at one end with a handle 12 eccentrically located with respect to the shaft 10 for the rotation of the cylinder 11.

A clamping member 13 in the form of a leaf spring has one end secured on the cylinder 11, as shown at 14, and the normal tendency of the clamping member is to engage in a groove of the

cylinder substantially throughout the length thereof. The free end of the clamping member extends out of the groove so that it may be gripped for flexing into the dotted line position as shown in Figure 3 to permit the cloth to be positioned thereunder and when freed is adapted to clamp the cloth on the periphery of the cylinder so that the cloth during the rotation of the cylinder will be caused to wind from the bolt onto the cylinder.

The external diameter of the cylinder is of a selected measurement and secured thereto and operating between flanges 15 provided on said cylinder 11 is a measuring tape 16. The measuring tape extends from the cylinder 11 and is wound on a spring influenced drum 17 journaled on arms 18 forming an integral part of the standards 9 and arranged in a plane below the cylinder so as to support the drum 17 laterally of the cylinder 11 and in a plane below the latter. A clock type spring 19 is used for driving the drum 17 in one direction and in a direction to wind the tape 16 onto said drum and also to position the cylinder 11 ready to receive the end of the cloth from the bolt of cloth. The cylinder when rotated to wind the cloth from the bolt onto the cylinder, the tape also will be wound onto said cylinder which will indicate the length of material wound on the cylinder permitting the operator to easily determine when a desired length of material has been wound on the cylinder 11 from the bolt of cloth. Also, if desired the tape 16 may be provided with a calculating table (not shown) to permit the clerk or operator to easily determine the price of the amount of cloth which has been wound onto the cylinder.

A cloth cutting frame 20 of substantially U shape is pivotally mounted by having one end pivoted on one of the uprights 9 and its other end pivoted on an upright 21 carried by the base 5. Normally when the cutting frame is not in use it occupies a horizontal position resting in notches 22 provided in the plates 8 of the rock or support 6. The frame 20 may be swung from the horizontal position to occupy a position with the bight portion disposed over the cylinder 11 and under the cloth, as shown in dotted lines in Figure 4. The bight portion of the frame is of a tubular construction and is provided with a slot 23. The cutting frame on being moved into the latter-named position, the bolt of cloth is lifted and it passes under the cloth, as shown in dotted lines in Figure 4, elevating the cloth away from the cylinder 11 and by using a knife or some other similar cutting instrument, as

shown in Figure 6, the cloth may be readily cut transversely thereof, the slot 23 permitting the cutting instrument to pass freely through the cloth and bring about an efficient severance of the cloth and also acting as a guide for the movement of the cutting instrument across the cloth so that the cloth will be cut with straight ends. A dog 25 is pivotally mounted on one of the standards 9 and normally rides the teeth of a gear 26 secured on one end of the cylinder 11 for the purpose of preventing the cylinder from rotating under the influence of the clock-type spring 19 when manually freed. However, this dog will permit the cylinder 11 to be manually rotated in a direction for winding the cloth onto the cylinder from the bolt of cloth and its purpose is to hold the cylinder 11 against rotation during the time of severing the cloth on the cutting frame and prior to removing the cloth from the cylinder which has been wound thereon.

After the cloth has been wound onto the cylinder 11 from the bolt to a desired length, which may be easily determined by referring to the tape measure 16, and after the severance of the cloth which is on the cylinder in the manner heretofore described, the operator pulls the cloth on the cylinder off of one end thereof or the end having the handle 12. The cloth removed from the cylinder in this manner when laid on a counter will assume a folded condition ready for wrapping.

After the first operation of removing from the bolt of cloth a desired length of cloth and severing the same from the cloth of the bolt of cloth through the use of the cutting frame, the latter is returned to its normal position within the notch 22, by removing the bolt of cloth from the rack 6. The operator then releases the dog 40 from the teeth of the gear and the drum 11 is returned to its initial position by the influence of the spring 19 which also winds the tape measure onto the drum 17.

It is believed that the simplicity and advantages of this invention will be perfectly apparent to those skilled in the art to which such device relates, and while I have herein set forth a satisfactory embodiment of my invention, it is to be understood that such changes therefrom as fairly fall within the scope of my claims may be resorted to when desired.

What is claimed is:

1. In a machine of the class described comprising a base, means for supporting a bolt of cloth on said base to permit the cloth to be unwound therefrom, a supporting means on the base, a cylinder rotatably supported by said supporting means and adapted to have cloth of the bolt wound thereon, clamping means on the cylinder for releasably securing the cloth thereto, a handle for rotating said cylinder and con-

nected to the unsupported end thereof and so positioned as to permit the cloth on the cylinder to be removed from the latter in an endwise direction of said cylinder after being severed from the cloth of the bolt, a substantially U-shaped frame pivotally mounted on said base and normally supported by said first-named means and capable of being moved in a position to substantially overlie and parallel said cylinder and to underlie the cloth passing from the bolt 10 to said cylinder for raising the cloth from the cylinder and having a slot in which a cutting instrument may enter during the severance of the cloth on said frame transversely of the cloth. 5

2. In a machine of the class described, a base, 15 a rack on said base for supporting a bolt of cloth to permit cloth to be unwound therefrom and having notches, supporting means on said base, a cylinder rotatably carried by said supporting means with one end thereof unobstructed, a 20 clamp carried by said cylinder for securing an end of the cloth of the bolt of cloth onto the cylinder, a handle on said cylinder for rotating the latter to wind cloth thereon, a substantially U-shaped cutting frame pivoted on said supporting means and normally occupying a position in the notches of the rack and adapted to be moved to overlie the cylinder and underlie the cloth passing from the bolt of cloth to the cylinder for supporting the cloth for cutting, 25 said frame having a groove to guide the cutting instrument when passing through the cloth in its movement transversely of the cloth, and a measuring means connected to the cylinder for determining the length of cloth wound thereon. 35

3. In a machine of the class described, a base, a rack on said base for supporting a bolt of cloth to permit cloth to be unwound therefrom and having notches, supporting means on said base, a cylinder rotatably carried by said supporting 40 means with one end thereof unobstructed, a clamp carried by said cylinder for securing an end of the cloth of the bolt of cloth onto the cylinder, a handle on said cylinder for rotating the latter to wind cloth thereon, a substantially U- 45 shaped cutting frame pivoted on said supporting means and normally occupying a position in the notches of the rack and adapted to be moved to overlie the cylinder and underlie the cloth passing from the bolt of cloth to the cylinder for supporting the cloth for cutting, said frame having a groove to guide the cutting instrument when passing through the cloth in its movement transversely of the cloth, a spring driven drum journaled on the base, a tape measure secured to 55 and wound on said drum and having one end secured to said cylinder for winding thereon during the rotation of the cylinder to indicate the length of material wound on said cylinder from the bolt of cloth. 50

HENRY C. DAVIS.
